UNITED STATES PATENT OFFICE.

OSWALD PFEIFFER, OF LEIPZIG, GERMANY.

APPARATUS FOR DRYING MATERIAL.

Application filed August 24, 1921. Serial No. 495,119.

To all whom it may concern:

Be it known that I, OSWALD PFEIFFER, a citizen of the German Republic, residing at Leipzig, Germany, have invented certain new and useful Improvements in Apparatus for Drying Material (for which I have filed application for patents in the following countries: in Czechoslovakia 26th June, 1920; Austria 1st July, 1920; Poland 7th 10 July, 1920; France 9th July, 1920; Belgium 10th July, 1920; Germany 20th August, 1918), of which the following is a specification.

This invention relates to a drying apparatus for grains and similar drying material in which hot air is conducted through the drying material spread out upon hurdles. It has already become known to arrange in drying apparatus of this type several superposed hurdles. The pockets which are thus formed are to be filled and emptied when the hurdles are in vertical position and the material is dried when said hurdles are in horizontal position.

With devices of this type of known construction the revolving of the hurdles from the horizontal into the vertical position and inversely is effected in such a manner that the hurdles mounted in portable frames are carried to the places where they have to be filled or emptied. With large hurdles and heavy drying material this means very heavy work requiring many hands. The plant requires further much space.

According to this invention these inconveniences are obviated by making a set composed of several hurdles and of an envelope for the same, revolvable around a horizontal axis. With this arrangement the hurdles can be turned from the horizontal into the vertical position and inversely with little power, eventually by mechanical drive. The whole plant requires little attendance and little space as the charging device can be arranged directly above the drying device and as the emptying can be effected directly into a chute or into a conveying device arranged below the drying apparatus so that the drying material is moved through the drying device merely by the action of its natural weight.

The hurdles consisting of perforated plates of sheet metal or of wire gauze are arranged in the well known manner so that always two of the plates of perforated sheet

metal or wire gauze are arranged at equal distances apart, form a pocket for the reception of the drying material, the air space between every two pockets serving for the admission or for the outflow of the drying air.

Devices of known construction can be further used for reversing the direction of the air current. The pockets have each one or two opposite obturable openings which are situated at the top when the pockets have to be filled and at the bottom when they have to be emptied.

In order that the invention may be clearly understood, I shall proceed to describe the same with reference to the two forms of construction differing the one from the other merely by the arrangement of the ventilating devices, shown by way of example in the accompanying drawings.

Fig. 1 is a longitudinal section of the drying apparatus on line *x*—*y* of Fig. 4.

Fig. 2 is a cross section on line *x*—*y* of Fig. 3 showing the drying apparatus in the position for being charged.

Fig. 3 is a similar cross section on line *x*—*y* of Fig. 2 showing the drying apparatus in the position for drying.

Fig. 4 shows the second form of construction in longitudinal section on line *x*—*y* of Fig. 1.

a are two oppositely situated pockets for the drying material formed by the perforated walls *b*.

The pockets have at one small end charging holes *d* closed by charging doors *e*. The pockets *a* are arranged in a casing *e* in such a manner that they alternate with air chambers *f*. Ports *g* connect the air chambers *f* alternately with the chambers *h* and *i*, arranged upon the end walls of casing *e* so that the air which flows through the drying apparatus must always traverse one pocket filled with drying material.

In the form of construction shown by way of example in Fig. 1 the ports *g* are closed by slides *k* adapted to be displaced in such a manner that the air is forced to flow along the path indicated by the arrows and to traverse the pockets *a* alternately from above and from below.

The slides are constructed as follows: Upon a rod *k* with handle *l* at the lower end three obturating slides are fixed which are of such a size that each slide can obturate

one of the ports g . If the rods k are in the positions shown in Fig. 1, air flows through ports 3 and 5 into the air channels, the other ports 8, 9, 10 being obturated by the slides 5 g . At the left end of the casing e (Fig. 1) the ports 5, 6, 7 are open so that the air can flow out, the ports 11, 12 being closed. The path followed by the air at the position of the slides shown on Fig. 1 is indicated by 10 the arrows in full lines. If the air has to flow in the direction indicated by the arrows in dash lines (Fig. 1) the rod k at the left hand end of casing e has to be pushed upward and the rod k at the right hand end 15 has to be pulled down. The case a is revolvable around the horizontal axis $y-z$ and mounted upon rollers o and it is revolved for charging and emptying by means of a simple driving gear p . If each pocket a has only 20 one charging hole the casing must be adapted to be turned of 180° . There can however be provided charging holes at the two opposite sides so that it is only necessary to turn the casing e of 90° . The hot air is forced into 25 chamber h by the air wheel l and it escapes from the chamber i through tube m . The air

conduits are connected with the chambers h and i by means of stuffing boxes q .

In the form of construction shown in Fig. 4 a reversing valve n is arranged behind the 30 air wheel l through which the hot air can be admitted alternately to either end of the drying apparatus.

I claim:—

An improved drying apparatus of the 35 type in which the material is charged between the hurdles and emptied from the same if said hurdles are in vertical position and dried when said hurdles are in horizontal position comprising in combination with the hurdles, a casing for the hurdles, means for the admission of the drying air to said casing and means for the escapement of the drying air from said casing, and means for turning said casing with the 40 hurdles around a horizontal axis. 45

In testimony whereof I affix my signature in presence of two witnesses.

OSWALD PFEIFFER.
